6 Claims. (Cl. 260—156)

This application is a continuation-in-part of our co-pending application, Ser. No. 296,502, filed July 22, 1963 (now abandoned).

The present application concerns new, water-dispersible azo dyestuffs, processes for the production thereof, processes for the dyeing of organic hydrophobic material using the new dyestuffs and, as industrial product, the materials dyed with the aid of these dyestuffs.

Dyeing of organic hydrophobic fibrous materials such as high molecular esters of aromatic polycarboxylic acids with polyfunctional alcohols, synthetic polyamide fibers and the like with the known disperse dyes are frequently not sufficiently fast; in particular, they often lack sufficient light fastness and fastness to sublimation, and the known disperse dyes lack drawing power on these materials.

It has now been found that compounds of the formula

wherein A represents unsubstituted phenyl or lower alkyl-phenyl, trifluoromethylphenyl, lower alkoxyphenyl, lower alkanoylaminophenyl, benzoylaminophenyl, nitrophenyl, cyanophenyl, fluorophenyl, chlorophenyl, bromophenyl, lower alkylcarbonylphenyl, benzoylphenyl, carbamyl-phenyl, mono-N-lower alkyl-carbamylphenyl, di-(N-lower alkyl) - carbamylphenyl, N - lower alkyl-N-phenyl-carbamylphenyl, piperidino - (1)-carbonylphenyl, morpholino - (1)-carbonylphenyl, lower alkoxy carbonylphenyl, phenoxy-carbonyl-phenyl or benzyloxy-carbamyl-phenyl, but no unsubstituted or N-substituted sulfamyl- or alkyl- or aryl-sulfonyl-phenyl radicals;

B represents hydrogen, alkyl with from 1 to 6 carbon atoms, cycloalkyl with from 5 to 6 carbon atoms, hydroxy-alkyl with from 1 to 4 carbon atoms, cyanoalkyl with from 1 to 4 carbon atoms, alkoxyalkyl with a total of from 3 to 6 carbon atoms the alkyl moiety of which radicals contains at least 2 carbon atoms, phenyl-lower alkyl, lower alkyl-phenyl-lower alkyl, chloro-phenyl-lower alkyl, bromo-phenyl-lower alkyl, phenyl, lower alkyl-phenyl, chloro-phenyl, bromo-phenyl, lower alkoxy-phenyl, lower alkanoylaminophenyl, naphthyl, lower alkyl-naphthyl, chloro-naphthyl or bromo-naphthyl, and

R represents one of the following radicals: primary alkyl with from 4 to 10 carbon atoms, secondary alkyl with from 4 to 10 carbon atoms, phenyl, lower alkyl-phenyl, lower alkoxy-phenyl, chloro-phenyl, bromo-phenyl, lower alkanoylaminophenyl, hydroxy-lower alkyl-phenyl, carbamyl-phenyl, mono-N-lower alkyl-carbamyl-phenyl, di - (N-lower alkyl) carbamyl-phenyl, lower alkoxy-carbonylphenyl, nitrophenyl, di - (lower alkyl)-amino-phenyl, phenoxy-phenyl, lower alkyl-phenoxy-phenyl, lower alkoxy-phenoxy-phenyl or pyridyl-(3) radicals; while cyclohexyl, chloro-phenoxy-phenyl, bromo-phenoxy-phenyl and phenyl-lower alkyl are second

2

choice as substituents R, wherein the substituent $-\text{SO}_2-\text{OR}$ is bonded directly to a benzene or a naphthalene nucleus in Formula I, and which compounds of Formula I are free from water-solubilizing groups which dissociate acid in water, are highly useful as disperse dyestuffs for the dyeing of hydrophobic, synthetic organic textile fibers from aqueous dispersion e.g. for the dyeing of cellulose di- or tri-acetate, particularly however, for the dyeing of high molecular esters of aromatic polycarboxylic acids with polyfunctional alcohols, e.g. of polyglycol terephthalates such as Terylene, Dacron, Tergal, or Trevira. Dyestuffs according to the invention are also useful for the dyeing of synthetic polyamide fibers such as nylon or of Perlon which dyeings are distinguished by their good fastness properties, among them fastness to washing (alkali, water, sea water, etc.) and to light and sublimation.

Moreover, light fast dyeings are obtained with the dyestuffs according to the invention on polyacrylonitrile fibers such as Orlon.

Dyestuffs of Formula I are also suited for use in dyeing acetate rayon, polyester fibers, polyamide fibers such as nylon and the like, in the mass, prior to spinning (dope dyeing) and also as pigments in lacquers and paints, because of their good solubility in organic solvents such as acetone, chloroform and the like.

Polyester fibers are dyed with aqueous dispersions of dyestuffs according to the invention preferably at temperatures of over 100° C. under pressure. Dyeing can also be performed, however, at the boiling point of the dyebath in the presence of carriers such as phenylphenol, polychlorobenzene compounds or similar auxiliaries, or by the foulard process after which the dyeing is thermofixed at 180–210° C.

The drawing power of the dyestuffs can be still further improved by mixing two or more monoazo dyestuffs according to the invention.

Dyestuffs according to the invention are distinguished by good affinity to hydrophobic polyesters fibers, particularly to polyglycol terephthalates and, depending on their composition, produce on these fibers greenish yellow to reddish yellow dyeings of good colour strength which have very good fastness to washing, sublimation, light, perspiration and cross-dyeing. In addition, vegetable and animal fibers, particularly cotton, are very well reserved by the dyestuffs according to the invention. They can also be dyed evenly with the usual commercial carriers.

Particularly satisfactory disperse dyestuffs which dye fast and with superior drawing power on the above-mentioned fibers, especially on polyethyleneglycol terephthalate fibers (e.g. Dacron), are the compounds of the formula

55 and

65

70 wherein B and R have the meaning given above,

A_1 is one of the radicals of the formulas

X_1 represents hydrogen, lower alkyl, lower alkoxy, $-Cl$, $-Br$, $-NO_2$, or $-CN$,

X_2 represents hydrogen, lower alkyl, lower alkoxy, $-Cl$, $-Br$, $-F$, or $-NO_2$,

X_3 represents hydrogen, $-Cl$, Br , $-CF_3$ or lower alkoxy-carbonyl, each of X_4 and X_5 , independently, represents hydrogen, lower alkyl, $-Cl$, $-Br$, or $-NO_2$,

and B_1 represents

phenyl,
lower alkyl-phenyl,
chloro-phenyl,
bromo-phenyl,
lower alkoxy-phenyl,
lower alkanoylamino-phenyl,
naphthyl,
lower alkyl-naphthyl,
chloro-naphthyl, or
bromo-naphthyl,

the radical $-SO_2-OR$ in Formula III being directly bonded to a benzene or naphthalene nucleus, of B_1 , and the compounds of Formulas II and III being free from water-solubilizing groups which dissociate acid in water.

Disperse dyestuffs with similar good proportion as those described in the foregoing, are those of the formula

wherein Y_1 represents hydrogen, lower alkyl, lower alkoxy, or hydroxy-lower alkoxy,

Y_2 represents hydrogen, lower alkyl, lower alkoxy, hydroxy-lower alkoxy, chlorine, bromine, fluorine or trifluoromethyl,

and B and R have the above given means, and wherein the substituent $-SO_2OR$ is directly bonded to an aromatic nucleus in Formula IV, i.e. either a benzene nucleus or a naphthalene nucleus, the compounds of Formula IV being free from water-solubilizing groups which dissociate acid in water.

Dyeings on the above-described hydrophobic fibers which have optimal fastness to light and sublimation are obtained with those disperse dyestuffs according to the invention which fall under the formula

wherein A_2 is one of the radicals

or

wherein X_6 represents hydrogen, chlorine, bromine, lower alkyl or lower alkoxy,
 X_7 represents hydrogen, chlorine, bromine, lower alkyl or lower alkoxy,

5 B_2 represents phenyl, lower alkyl-phenyl, chloro-phenyl, or bromo-phenyl, and

R_1 represents phenyl, lower alkyl-phenyl, lower alkoxy-phenyl, chloro-phenyl, bromo-phenyl, hydroxy-lower alkyl-phenyl, lower alkanoylamino-phenyl, lower alkoxy-carbonyl-phenyl, carbamyl-phenyl, mono- and di-(N-lower alkyl)-carbamyl-phenyl, or pyridyl-(3).

The substituent $-SO_2-OR_1$ in the compounds of Formula V being bonded directly to the benzene nucleus in B_2 , and the said compounds being free from water-solubilizing substituents which dissociate acid in water.

15 The term "lower" in connection with aliphatic radicals means that these radicals have from 1 to 4 carbon atoms.

Similar results are obtained with compounds of Formula V in which A_2 represents

20 preferably 2,4,6-trichlorophenyl.

The novel dyestuffs according to the invention are produced by coupling the diazonium compound of an amine of the formula

25 with a coupling component of the formula

30 of which two reactants either the diazo compound or the coupling component contains a substituent $-SO_2OR$, bonded directly to an aromatic (benzene or naphthalene) nucleus; A, B and R in Formulas VI and VII having the above given meanings.

In one group of coupling components which are suitable for use in the above reaction, B in Formula VII is either an aliphatic or a cycloaliphatic radical such as the methyl, ethyl, propyl, isopropyl, butyl, methoxypropyl, or cyanoethyl group or the cyclohexyl radical. When B is an aliphatic radical, it is, for example, the benzyl group; when it is an aromatic radical, it is, for example, an unsubstituted or a substituted phenyl or naphthyl radical.

35 In the substituent $-SO_2OR$, the radical $-OR$ represents, for example, an alkoxy group which is derived from n- or sec. butanol, or from a primary or secondary amyl or hexyl alcohol, or it is a cycloalkoxy group, e.g. the cyclohexyloxy radical, or an unsubstituted or substituted

40 aryloxy group which is derived, e.g. from a hydroxy-naphthalene such as a 1-hydroxy- or 2-hydroxy-naphthalene or preferably from a monohydroxybenzene such as phenol, an alkyl-, alkoxy-, or hydroxyalkyl-hydroxybenzene, or an aryloxy-, halogeno-, dialkyl-amino-, N-

45 alkyl-N-phenylamino-, alkoxy carbonyl-, carbamyl, or alkanoylamino-hydroxybenzene, i.e. it is derived, for example, from 2-, 3- or 4-methyl- or 2-, 3- or 4-ethyl- 1-hydroxybenzene or technical mixtures thereof, from 3,4- or 2,4-dimethyl-, 4-sec. butyl-, 4-isoctyl-, 2-, 3- or 4-chloro-, 2,4-dichloro-, 2-, 3- or 4-methoxy, 2-, 3- or 4-ethoxy-, 4-

50 phenoxy-, 3-dimethylamino-, 3-diethylamino-, 2,4-dicarbomethoxy- or 2,4-di-carboethoxy-1-hydroxybenzene, 2-hydroxymethyl-1-hydroxybenzene, 2-acetylamino-1-hydroxybenzene or 3-acetylamino-1-hydroxybenzene.

55 Examples of substituents of the benzene ring of A are: aliphatic groups such as methyl, trifluoromethyl, ethyl, propyl or isopropyl groups, alkoxy groups such as methoxy, ethoxy or butoxy groups, acylamino, especially lower alkanoylamino groups such as acetylamino, or benzoyl-amino groups, particularly however, electrophilic substitu-

ents such as nitro groups, the trifluoromethyl or cyano groups mentioned above, halogens, in particular fluorine, chlorine or bromine, keto groups such as acetyl, propionyl or benzoyl groups, and, when the substituent $-\text{SO}_2-\text{OR}$ is at the B-moiety, carboxylic acid ester groups such as the carbomethoxy, carboethoxy, carboisopropoxy, carbobutoxy, or carbophenoxy group, or unsubstituted or substituted carbamyl or sulfamyl groups.

In the compounds in which ring A contains an arylazo group, the latter is preferably a phenylazo group the benzene ring of which is unsubstituted or contains the substituents previously mentioned. In the compounds of Formula I in which B presents an aliphatic or an aromatic radical, the rings of that radical are either unsubstituted or substituted, for example, by halogens such as chlorine or bromine, particularly in a position adjacent to the bond to the pyrazolene nucleus as well as by lower alkyl or alkoxy groups or acylamino, especially lower alkanoylamino groups.

Dyestuffs of Formula I substituted at the benzene ring of A by an arylazo group produce more reddish yellow dyeings; when A does not contain an arylazo group, very pure, more greenish yellow dyeings are obtained.

When diazonium compounds of amines of Formula VI usable according to the invention contain the characteristic SO_2OR group, then these are, for example, esters of the alcohols, naphthols and, particularly, phenols mentioned above in the discussion of the group $\text{RO}-$, which are derived, for example, from 1-aminobenzene-2-, -3- or -4-sulphonic acid, 2-alkyl-1-aminobenzene- or 2-halogen-1-aminobenzene- -4- or 5-sulphonic acids, 3-alkyl-1-aminobenzene-4-sulfonic acid, 4-alkyl-1-aminobenzene- or 4-halogen-1-aminobenzene-2-sulphonic acids, or 2,5-dichloro-1-aminobenzene-4-sulphonic acid, 3,4-dichloro-1-aminobenzene-6-sulfonic acid and 2-chloro-3-methyl-1-aminobenzene-6-sulfonic acid.

Coupling components of Formula VII usable according to the invention which contain the SO_2OR group as defined are esters of the hydroxyl compounds mentioned with, e.g. 1-phenyl-3-methyl-pyrazol-5-one, 2', -3' or -4'-sulphonic acid, 1-(4'-methyl-phenyl)-3 - methyl-pyrazole-5-one-3'-sulphonic acid, 1 - (2'-chloro-phenyl)-3-methyl-pyrazol-5-one-5'-sulphonic acid, 1-(2',5'-di-chlorophenyl)-3-methyl-pyrazol-5-one-4'-sulphonic acid.

Amines of Formula VI containing sulphonic acid ester groups are obtained, for example, by reacting the desired alcohol, naphthol or phenol with the corresponding nitrobenzene sulphonic acid chloride or bromide and then reducing the nitro group to the amino group.

Sulfonic acid ester substituted pyrazolones of Formula VII which serve as coupling components for producing dyestuffs according to the invention are produced by esterification of the corresponding starting compound of the formula

wherein B has the above given meaning, with the corresponding hydroxylated compound of the formula

wherein R has the meaning given above, reduction of the nitro group of the resulting nitro ester to the corresponding amino ester, conversion to the hydrazino ester and condensation of the latter with an acetoacetic acid ester.

Examples of amines of Formula VI free from the characteristic sulphonic acid ester group which are used according to the invention are

- 1-amino-2-nitrobenzene,
- 1-amino-2-nitro-4-methyl-benzene,
- 1-amino-2-nitro-4-methoxy- or
- 4-ethoxy-benzene,
- 1-amino-2-nitro-4-chloro-,
- 4-fluoro- or -4-bromo-benzene,
- 1-amino-2-nitro-4-trifluoromethyl-benzene,

- 1-amino-4-nitrobenzene,
- 1-amino-4-nitro-2-methylbenzene,
- 1-amino-4-nitro-2-methoxy- or
- 2-ethoxy-benzene,
- 5 1-amino-4-nitro-2-chloro-,
- 2-fluoro- or -2-bromo-benzene,
- 1-amino-4-nitro-2-cyanobenzene,
- 1-amino-4-nitro-2,5-di-chlorobenzene,
- 1-amino-4-nitro-2,6-dichloro- or
- dibromo-benzene,
- 1-amino-2,4-dinitrobenzene,
- 1-amino-2-4-dinitro-6-chlorobenzene or
- 1-amino-2,4-, -2,5- or 3,4-dicyanobenzene,
- 15 4-nitro-3-carbethoxy-1-amino-benzene,
- 4-nitro-2-carbethoxy-1-amino-benzene,
- 1-amino-2-chlorobenzene,
- 1-amino-3-chlorobenzene,
- 1-amino-4-chlorobenzene,
- 1-amino-2,4-chlorobenzene,
- 1-amino-2,5-dichlorobenzene,
- 1-amino-3,4-dichlorobenzene,
- 1-amino-2,6-dichlorobenzene,
- 1-amino-2,4,5-trichlorobenzene,
- 4-amino-azobenzene,
- 25 4-amino-2',
- 3-dimethyl-azobenzene,
- 4-amino-2,5-dimethoxy-3'-methyl-azobenzene,
- 4-amino-2-methyl-5-methoxy-4'-hydroxyethoxy-azobenzene
- 30 and 4-amino-2-methyl-5-methoxy-3'-hydroxyethoxy-azobenzene.

Examples of coupling components of Formula II without the defined SO_2OR group are 3-methyl-pyrazol-5-one, 1,3-dimethyl-pyrazol-5-one, 3-methyl-pyrazol-5-one which are substituted in 1-position by ethyl, propyl, isopropyl, β -hydroxyethyl, β -cyanoethyl, cyclohexyl, benzyl, phenyl, 2'-methyl-phenyl, 3'-methyl-phenyl, 4'-methyl-phenyl, 2'-methoxy-phenyl, 3'-methoxy-phenyl, 4'-methoxy-phenyl, 2'-chloro-phenyl, 4'-chloro-phenyl, 2',4'-dichloro-phenyl, 2',4'-dibromo-phenyl, 3'-acetyl-amino-phenyl or 4'-acetyl-amino-phenyl.

The coupling is performed in mineral acid or, preferably, in weakly acid solution advantageously, while gradually buffering the acid, e.g., with alkali metal salts of carbonic acid or low fatty acids. If desired, a suitable diazonium compound can also be coupled simultaneously with a mixture of two or more coupling components which are usable according to the invention.

A modification of the process for the production of azo dyestuffs consists in condensing an azo compound of formula

wherein A represents a phenyl radical which can also contain phenyl azo groups,

60 B represents hydrogen or an aliphatic, cycloaliphatic, or aromatic radical,
X represents chlorine or bromine and the SO_2-X group is directly bound to an aromatic, carbocyclic nucleus, with an organic hydroxyl compound of formula

wherein R' represents an alkyl radical containing at least 4 carbon atoms or a cycloalkyl radical or an unsubstituted or a substituted aryl radical,

70 to form the corresponding compound of Formula I, the components being so chosen that the resulting dyestuff does not contain any water-solubilizing groups which dissociate acid in water.

Naturally, the remarks regarding A, B and $-\text{SO}_2-\text{OR}$ in the first process also apply to this process variation.

The starting materials of the Formula VIII are obtained, for example, by coupling the diazonium compound of an amine of Formula VI with a coupling component of Formula VII, one of which components contains the sulfonic acid group, directly bound to an aromatic, carbocyclic nucleus, and converting the azo dyestuff sulfonic acid so obtained to the corresponding sulfonic acid chloride, or bromide, for example by means of a phosphorus halide or thionyl chloride, without or in the presence of a tertiary nitrogen base and an inert solvent or diluent. Examples of suitable amines of Formula VI and of coupling components of Formula VII are the 1-aminobenzenes or 3-methyl-pyrazol-5-ones respectively or the sulfonic acids of these compounds mentioned in the first process, as well as 2-nitro-1-aminobenzene - 4-sulfonic acid, 4-nitro-1-amino-benzene-2-sulfonic acid, 5 - chloro-2-nitro-1-amino-benzene-4-sulfonic acid, 4-amino-azobenzene-4'-sulfonic acid, 2-methyl-4-amino-azobenzene-4'-sulfonic acid and 2-methyl-4-amino-azobenzene-3'-sulfonic acid.

Examples of organic hydroxyl compounds of Formula IX which are to be reacted with the sulfonic acid chlorides or bromides of Formula VIII are those mentioned in the illustration of RO—.

The condensation of compounds of Formula VIII with the hydroxyl compounds of Formula IX to form esters of Formula I is performed advantageously at a raised temperature, optionally in aqueous, organic or aqueous/organic solution. Suitable organic solvents for this purpose are those which are miscible with water, e.g., lower alkanols, especially methanol or ethanol, lower aliphatic ketones such as acetone or methylethyl ketone, or ether alcohols such as ethylene glycol monomethyl or monoethyl ether, or those which are not miscible with water, e.g., unhalogenated or halogenated aromatic hydrocarbons such as benzene, toluene, xylenes, chlorobenzene or dichlorobenzenes. The hydroxyl compounds to be reacted, such as the hydroxyalkyl, hydroxycycloalkyl or hydroxyaryl compounds, are advantageously used in the form of their metal salts such as the sodium or potassium salts.

The following non-limitative examples illustrate the invention. Where not otherwise expressly stated, parts and percentages are by weight. The temperatures are in degrees centigrade. The relationship of parts by weights to parts by volume is as that of grams to cubic centimeters.

EXAMPLE 1

34.4 parts of 1-phenyl-3-methyl-pyrazole-5-one-3'-sulphonic acid-(4"-methylphenyl)-ester are dissolved in 100 parts of dimethyl formamide and the solution is poured into 400 parts of water and 6 parts of cetyl polyglycol ether while stirring quickly. The diazonium salt solution of 17.3 parts of 1-amino-2-chloro-4-nitro-benzene is added dropwise at 0-5° to the fine dispersion and then the free mineral acid is buffered by the addition of sodium acetate. On completion of the coupling, the precipitate formed is filtered off, washed with a great deal of water and dried in vacuo at 60-70°. The coupling product is a red-orange powder, the composition of which corresponds to the formula

Milled with a condensation product of naphthalene sulphonic acids and formaldehyde, the dyestuff so obtained dyes polyglycol terephthalate fibres such as Dacron in vivid yellow shades from aqueous dispersion, if necessary in the presence of carriers such as o-phenylphenol. The

bath is substantially exhausted. The dyeings have excellent fastness to washing, sublimation and light.

The 1-phenyl-3-methyl-pyrazole-5-one - 3' - sulphonic acid-(4"-methylphenyl)-ester used for the coupling is obtained for example by reacting 1-nitrobenzene-3-sulphonic acid chloride with p-cresol, reducing the nitro group to the amino group, converting the 1-aminobenzene-3-sulphonic acid-(4"-methylphenyl)-ester into the corresponding hydrazine and condensing the 1-hydrazino-benzene-3-sulphonic acid-(4"-methylphenyl)-ester with acetoacetic acid methyl ester.

If, instead of the 34.4 parts of 1-phenyl-3-methyl-pyrazole-5-one-3'-sulphonic acid - (4"-methylphenyl)-ester, a corresponding amount of the coupling components given in Table I is used and they are coupled under the conditions given in the above example, then dyestuffs are obtained which produce dyeings on polyester fibres which have equally good properties.

TABLE I

No.	Diazo component	Coupling component	Shade on polyester fibres
25 1	1-amino-4-nitro-2-chlorobenzene.	1-phenyl-3-methyl-pyrazole-5-one-3'-sulphonic acid phenyl ester.	Yellow.
2	do	1-phenyl-3-methyl-pyrazole-5-one-3'-sulphonic acid-(2"-methylphenyl)-ester.	Do.
3	do	1-phenyl-3-methyl-pyrazole-5-one-3'-sulphonic acid-(3"-methylphenyl)-ester.	Do.
30 4	do	1-phenyl-3-methyl-pyrazole-5-one-3'-sulphonic acid-(2"-chlorophenyl)-ester.	Do.
5	do	1-phenyl-3-methyl-pyrazole-5-one-3'-sulphonic acid-(4"-chlorophenyl)-ester.	Do.
35 6	do	1-phenyl-3-methyl-pyrazole-5-one-3'-sulphonic acid-(2"-dichlorophenyl)-ester.	Do.
7	do	1-phenyl-3-methyl-pyrazole-5-one-3'-sulphonic acid-(3"-methoxyphenyl)-ester.	Do.
8	do	1-phenyl-3-methyl-pyrazole-5-one-3'-sulphonic acid-(4"-tert.butylphenyl)-ester.	Do.
40 9	do	1-phenyl-3-methyl-pyrazole-5-one-3'-sulphonic acid-(4"-carboethoxyphenyl)-ester.	Do.
10	do	1-phenyl-3-methyl-pyrazole-5-one-3'-sulphonic acid-(4"-phenoxyphenyl)-ester.	Do.
45			

EXAMPLE 2

The diazonium salt solution from 19.7 parts of 4-amino-azobenzene prepared in the usual way is added dropwise at 0-5° while cooling to a suspension of 33.0 parts of 1-phenyl-3-methyl-5-pyrazolone-4'-sulphonic acid phenyl ester in a mixture of 100 parts of dimethyl formamide, 1500 parts of water, 120 parts of crystallised sodium acetate and 5 parts of a fatty acid polyethylene oxide condensation product. The coupling begins immediately. The orange-yellow precipitate formed is filtered off under suction, washed neutral with water and dried in vacuo at 60-70°. The dyestuff corresponds to the formula

After milling with a condensation product of naphthalene sulphonic acids and formaldehyde, it dyes polyglycol terephthalate fibres such as Dacron in reddish yellow

shades from an aqueous dispersion, sometimes in the presence of o-phenylphenol. The dyeings have excellent fastness to washing, light and sublimation.

The 1-phenyl-3-methyl-pyrazole-5-one - 4' - sulphonic acid phenyl ester used as starting material is obtained by reacting 1-nitrobenzene-3-sulphonic acid chloride with phenol, reducing the nitro group to the amino group, converting the amine into 1-hydrazino-benzene - 3 - sulphonic acid phenyl ester and condensing this with acetoacetic acid methyl ester.

Dyestuffs having similar properties are obtained if, instead of the 33.0 parts of 1-phenyl-3-methyl-pyrazole-5-one-4'-sulphonic acid phenyl ester, the equivalent amounts of 1-phenyl-3-methylpyrazole-5-one-4' - sulphonic acid-(2"-methylphenyl)-ester, 1-phenyl-3 - methylpyrazole-5-one-4'-sulphonic acid-(3"-methylphenyl)-ester, 1-phenyl-3-methylpyrazole-5-one-4'-sulphonic acid-(4"-methylphenyl)-ester or 1-phenyl-3-methylpyrazole - 5 - one - 4'-sulphonic acid - (2" - chlorophenyl) - ester, 1 - phenyl-3-methylpyrazole - 5 - one - 3' - sulphonic acid - (2"-methylphenyl)-ester or 1-phenyl-3-methylpyrazole - 5-one-3'-sulphonic acid phenyl ester, 1-phenyl-3-methylpyrazole-5-one-3'-sulphonic acid-(2"-chlorophenyl)-ester are used.

EXAMPLE 3

Nitrosyl sulphuric acid, corresponding to 6.9 parts of sodium nitrite, is slowly added dropwise to a solution of 16.3 parts of 1-amino-4-nitro-2-cyanobenzene in 100 parts of concentrated sulphuric acid and the reaction mixture is kept for 3 hours at room temperature. The solution of the diazonium salt so obtained is then poured into a slurry of 36.5 parts of 1-(2'-chlorophenyl)-3-methylpyrazole-5-one-5'-sulphonic acid-(4"-methylphenyl)-ester and 120 parts of crystallised sodium acetate in 150 parts of dimethyl formamide and 1500 parts of ice water whereupon the yellow azo dyestuff of the formula

50

precipitates. The pH of the coupling solution is maintained at 4-5 by the simultaneous addition dropwise of sodium hydroxide solution. On completion of the coupling, the dyestuff is filtered off, washed neutral with water and dried in vacuo at 60-70°.

The 1-(2'-chlorophenyl) - 3-methylpyrazole-5-one-5'-sulphonic acid-(4"-methylphenyl)-ester used as coupling component is obtained analogously to the coupling component mentioned in Example 2 starting from 4-nitro-2-chlorobenzenes-5-sulphonic acid chloride and p-cresol.

A dyestuff preparation milled with the condensation product of naphthalene sulphonic acids and formaldehyde which contains the dyestuff in fine distribution dyés polyglycol terephthalate fibres such as Terylene in pure greenish yellow shades from an aqueous dispersion, sometimes in the presence of carriers. The dyeings have excellent fastness to washing, rubbing and sublimation.

If in the above example, instead of the 16.3 parts of 1-amino-4-nitro-2-cyanobenzene, corresponding amounts of the amines given in the following Table II are used and these are coupled under the conditions described in the example with the corresponding amount of a pyrazolone derivative given in column 3, then dyestuffs are obtained which produce dyeings on polyester fibres having equally good properties.

19	19	1-amino-2-nitro-4-methoxybenzene.	Yellow.
45	20	do	Greenish yellow.

EXAMPLE 4

15.1 parts of 1-amino-2-nitro-4-methylbenzene are diazotised in the usual way and coupled with 28.8 parts of 1-(2'-chlorophenyl) - 3 - methylpyrazole-5-one-3'-sulphonic acid. The dyestuff so obtained is dried, and converted with phosphorus oxychloride in an inert solvent in the presence of catalytic amounts of pyridine, into the corresponding sulphonic acid chloride.

7 parts of this dyestuff acid chloride, 4 parts of 4-chloro-1-hydroxybenzene and 14 parts of sodium carbonate in a mixture of 100 parts of water and 30 parts of ethyl alcohol are boiled for 16 hours while stirring vigorously. After cooling the reaction mixture to room temperature, the yellow dyestuff is filtered off, washed in a lot of water and dried in vacuo at 60-70°. The product so obtained has the formula

70

75

11

A preparation produced by milling the dyestuff with a condensation product of naphthalene sulphonic acids and formaldehyde dyes polyglycol terephthalate fibres such as Terylene or cellulose triacetate fibres in pure yellow shades from an aqueous dispersion, if necessary in the presence of carriers such as o-phenylphenol. The dyeings are fast to washing, sublimation and light.

EXAMPLE 5

An azo dyestuff is prepared by coupling diazotised 1-amino-4-methoxybenzene with 1-phenyl-3-methylpyrazole-5-one-3'-sulphonic acid. 38.8 parts of the well dried azo dyestuff are converted into the corresponding acid chloride in the usual way with phosphorus oxychloride in chlorobenzene in the presence of a little pyridine.

A slurry of 28 parts of the dyestuff acid chloride so obtained in a mixture of 600 parts of water and 120 parts of ethyl alcohol, 64 parts of sodium carbonate and 24 parts of 2-methyl-1-hydroxybenzene is heated for 15 hours at 70-80° while stirring. The reaction mixture is

12

then cooled to room temperature and the yellow dyestuff corresponding to the formula

is filtered off and washed with a lot of water. The product when dried in vacuo at 60-70° is a yellow powder.

15 A preparation produced by milling the dyestuff with a condensation product of naphthalene sulphonic acids and formaldehyde dyes polyglycol terephthalate fibers such as Terylene or cellulose triacetate fibers in greenish yellow shade from an aqueous dispersion, sometimes in the presence of carriers such as o-phenylphenol. The dyeings are 20 fast to washing and sublimation.

If in the above example, instead of the 28 parts of the dyestuff acid chloride mentioned, corresponding amounts of the acid chlorides mentioned in the following table are 25 used and they are coupled under the conditions described with one of the hydroxyaryl compounds given in column 3, then yellow dyestuffs are obtained which produce polyester dyeings having equally good dyeing properties.

EXAMPLE 6

A fine suspension of 13.7 parts of 1-amino-2-nitrobenzene in 500 parts of water, 60 parts of 36% hydrochloric acid and 5 parts of cetyl polyglycol ether is diazotised in the usual way at 5–7° by the addition of 6.9 parts of sodium nitrite. A solution of 38.0 parts of 1-(2'-chlorophenyl)-3-methylpyrazole-5-one-5'-sulphonic acid-(2"-methylphenyl)-ester in 125 parts of dimethyl formamide is added dropwise at 0–5° to the clear diazonium salt solution, and the mineral acid is buffered by the addition of sodium ace-

65 tate. On completion of the coupling, the dyestuff of the formula

is filtered off, washed with water, dried in vacuo at 60-70° and milled with a mixture of a condensation product of naphthalene-2-sulphonic acid with formaldehyde and a lignin sulphonate. The dyestuff is a yellow powder which dyes polyglycol terephthalate fibres in pure greenish yellow shades from an aqueous dispersion if necessary in the presence of a carrier such as o-phenylphenol. The dyeings have very good fastness to washing, rubbing, light and sublimation.

The 1-(2'-chlorophenyl)-3-methylpyrazole-5-one-5'-sulphonic acid-(2"-methylphenyl)-ester used as coupling component is obtained, for example, by reacting 1-nitro-2-chlorobenzene-5-sulphonic acid chloride with o-cresol, reducing the nitro group to the amino group, converting the 1-amino-2-chloro-5-sulphonic acid (2"-methylphenyl)-ester into the corresponding hydrazine and condensing this with acetoacetic acid methyl ester.

EXAMPLE 7

A slurry of 28 parts of 1-phenyl-3-methyl-4-(2"-nitro-4"-chlorophenylazo)-pyrazole-5-one-3'-sulphonic acid chloride in a mixture of 300 parts of water, 200 parts of ethyl alcohol, 20 parts of sodium carbonate and 20 parts of 3-methyl-1-hydroxybenzene is heated for 16 hours at 70-80°. The reaction mixture is then cooled to 10°, and the yellow dyestuff, the composition of which corresponds to the formula

is filtered off and washed with a lot of water. After drying in vacuo at 60-70°, the product is a yellow powder. It is not soluble in hot water but is easily soluble in organic

solvents, e.g. chloroform or acetone. The dyestuff can be used for the dyeing of lacquers, e.g. nitro lacquers or stoving lacquers, and for the dyeing of acetyl cellulose in the mass. Acetyl cellulose dyed therewith in the spinning 5 mass has a pure yellow shade and has good wet fastness and very good light fastness properties.

The 1-phenyl-3-methyl-4-(2"-nitro-4"-chlorophenylazo)-pyrazole-5-one-3'-sulphonic acid chloride used as starting material is obtained by coupling diazotised 10 amino-2-nitro-4-chlorobenzene with 1-phenyl-3-methyl-pyrazole-5-one-3'-sulphonic acid and reacting the dry dyestuff sulphonic acid with phosphorus oxychloride in chlorobenzene in the presence of catalytic amounts of pyridine.

EXAMPLE 8

15 17.3 parts of 1-amino-4-nitro-2-chlorobenzene are diazotised analogously to Example 1 and coupled with 25.4 parts of 1-phenyl-3-methylpyrazole-5-one-3'-sulphonic acid. The dried dyestuff so obtained is converted into the 20 corresponding sulphonic acid chloride with phosphorus oxychloride in an inert solvent in the presence of catalytic amounts of pyridine.

7 parts of this dyestuff acid chloride, 4 parts of 4-methyl-1-hydroxybenzene and 14 parts of sodium carbonate are 25 boiled for 16 hours, while stirring vigorously, in a mixture of 100 parts of water and 30 parts of ethyl alcohol. After cooling the reaction mixture to room temperature, the yellow dyestuff is filtered off, washed with a lot of water and dried in vacuo at 60-70°. The product so obtained has the formula

30

and is identical with the dyestuff obtained according to Example 1.

Dyestuffs having similar properties are obtained if 45 equivalent amounts of the sulphonic acid chlorides given in the following Table IV are coupled under the conditions described in the above example with corresponding amounts of the hydroxyaryl compounds shown therein.

TABLE IV

20		2-methyl-1-hydroxybenzene	Greenish yellow.

EXAMPLE 9

A dyestuff acid chloride is prepared by treating the dyestuff obtained by coupling diazotised 1-amino-4-nitro-2,6-dichlorobenzene with 1-(2',5'-dichlorophenyl)-3-methyl-pyrazole-5-one-4'-sulphonic acid with phosphorus oxychloride in tetrachloromethane in the presence of catalytic amounts of N,N-dimethyl aniline. 7 parts of this dyestuff acid chloride are slurred in 150 parts of water and 30 parts of ethanol and, after the addition of 14 parts of sodium carbonate and 6 parts of 4-methyl-1-hydroxybenzene, the reaction mixture is boiled for 18 hours while stirring well. The precipitated dyestuff obtained after cooling the reaction mass is washed with a lot of water and dried in vacuo at 60-70°. It corresponds to the formula

yellow shades from an aqueous dispersion, sometimes in the presence of carriers. The dyeings are fast to washing, rubbing and have excellent fastness to sublimation.

Similar dyestuffs are obtained under the conditions

given in the above example if equivalent amounts of the sulphonic acid chlorides given in column 2 of the following Table V are condensed with equivalent amounts of the hydroxyaryl compounds given in column 3.

TABLE V

No.	Sulphonic acid chloride	Hydroxyaryl compound	Shade on polyester fibres
1		4-methyl-1-hydroxybenzene	Yellow.
2		2-methyl-1-hydroxybenzene	Greenish yellow.
3		4-t-butyl-1-hydroxybenzene	Yellow.
4		4-methyl-1-hydroxybenzene	Do.
5		3-methyl-1-hydroxybenzene	Greenish yellow.
6		4-chloro-1-hydroxybenzene	Yellow.

10.....		4-t-butyl-1-hydroxybenzene.....	Do.
11.....		3-dimethylamino-1-hydroxybenzene.....	Do.
12.....		2-methyl-1-hydroxybenzene.....	Do.

TABLE V—Continued

No.	Sulphonic acid chloride	Hydroxyaryl compound	Shade on polyester fibres
13		2-acetylaminol-1-hydroxybenzene	Reddish yellow.
14		2-methyl-1-hydroxybenzene	Do.
15		3-methyl-1-hydroxybenzene	Do.
16		2-hydroxymethyl-1-hydroxybenzene	Do.
17		Hydroxybenzene	Do.

EXAMPLE 10

1-aminobenzene-3-sulphonic acid is diazotised in the known manner and coupled with 1-phenyl-3-methylpyrazole-5-one. The dried azo dyestuff is converted into the corresponding dyestuff acid chloride in chlorobenzene with phosphorus oxychloride in the presence of a little pyridine as catalyst.

6 parts of 2-methyl-1-hydroxybenzene and 20 parts of sodium carbonate are added to 10 parts of this acid chloride in a mixture of 120 parts of water and 40 parts of ethanol and then the reaction mass is boiled for 12 hours while stirring. After cooling the reaction mixture, the dyestuff formed is filtered off under suction, washed

with water and dried in vacuo. It corresponds to the formula

A dye preparation milled with a naphthalene sulphonic acid/formaldehyde condensation product which contains

the dyestuff in fine distribution, dyes polyglycol terephthalate fibres such as Trevira in pure yellow shades from an aqueous dispersion, sometimes in the presence of carriers such as o-phenylphenol. The dyeings are fast to washing, rubbing and light.

Dyestuffs having similar properties are obtained if, instead of 2-methyl-1-hydroxybenzene in the above example, the equivalent amount of 4-methyl-1-hydroxy-

benzene, 2-chloro-1-hydroxybenzene, 2,4 - dichloro-1-hydroxybenzene, 3-methoxy-1-hydroxybenzene or 4-t.butyl-1-hydroxybenzene is used.

Similar dyestuffs are obtained under the above conditions if equivalent amounts of the sulphonic acid chlorides given in column 2 of the following table are condensed with the corresponding amounts of the hydroxyaryl compounds listed in column 3.

TABLE VI

No.	Sulphonic acid chloride	Hydroxyaryl compound	Shade on polyester fibres
1.....		4-methyl-1-hydroxybenzene.....	Yellow.
2.....		4-t. butyl-1-hydroxybenzene.....	Do.
3.....		4-methyl-1-hydroxybenzene.....	Greenish yellow.
4.....		do.....	Yellow.
5.....		2.methyl-1-hydroxybenzene.....	Do.
6.....		2-chloro-1-hydroxybenzene.....	Greenish yellow.

9.....		4-chloro-1-hydroxybenzene.....	Do.
10.....		2-methyl-1-hydroxybenzene.....	Do.
11.....		Hydroxybenzene.....	Yellow.
12.....		2-hydroxymethyl-1-hydroxybenzene.....	Reddish yellow.
13.....		Hydroxybenzene.....	Do.

EXAMPLE 11

1-aminobenzene-4-sulphonic acid is diazotised in the usual way and coupled with 3-methylpyrazole-5-one. The dyestuff is well dried and then converted into the corresponding dyestuff acid chloride with phosphorus oxychloride in an inert solvent such as chlorobenzene in the presence of catalytic amounts of pyridine. 24 parts of sodium carbonate and 11 parts of 4-aminobenzene are added to a suspension of 12 parts of this acid chloride in a mixture of 150 parts of water and 50 parts of ethanol,

75

whereupon the reaction mass is boiled for 14 hours while stirring. After cooling to room temperature, the yellow dyestuff is filtered off under suction, washed neutral with water and dried in vacuo at 60-70°. It is a yellow powder which corresponds to the formula

A dye preparation milled with a naphthalene sulphonic acid/formaldehyde condensation product which contains the dyestuff in fine distribution, dyes polyglycol terephthalate fibres such as Dacron in yellow shades from an aqueous dispersion, if necessary in the presence of a carrier such as o-phenylphenol. The dyeings have good dyeing properties.

Similar dyestuffs are obtained under the conditions described above if equivalent amounts of the sulphonic acid chlorides given in column 2 of the following table are condensed with the equivalent amounts of hydroxyaryl compounds given in column 3.

TABLE VII

No.	Sulphonic acid chloride	Hydroxyaryl compound	Shade on polyester fibres
1.....		4-methyl-1-hydroxybenzene.....	Greenish yellow.
2.....		4-chloro-1-hydroxybenzene.....	Do.
3.....		4-methyl-1-hydroxybenzene.....	Do.
4.....		Hydroxybenzene.....	Do.
5.....		2-methyl-1-hydroxybenzene.....	Do.
6.....		2-methyl-1-hydroxybenzene.....	Greenish yellow.
7.....		4-methyl-1-hydroxybenzene.....	Do.

TABLE VII—Continued

No.	Sulphonic acid chloride	Hydroxyaryl compound	Shade on polyester fibres
8.....		4-amyl-1-hydroxybenzene.....	Greenish yellow.
9.....		3-methyl-1-hydroxybenzene.....	Yellow.
10.....		Hydroxybenzene.....	Do.
11.....		3-carbobutoxy-1-hydroxybenzene.....	Do.
12.....		4-chloro-1-hydroxybenzene.....	Greenish yellow.
13.....		2-chloro-1-hydroxybenzene.....	Do.
14.....		Hydroxybenzene.....	Do.

TABLE VII—Continued

No.	Sulphonic acid chloride	Hydroxyaryl compound	Shade on polyester fibres
15....		2-methyl-1-hydroxybenzene.....	Yellow.
16....		3-diethylamino-1-hydroxybenzene.....	Do.
17....		4-methyl-1-hydroxybenzene.....	Greenish yellow.
18....		Hydroxybenzene.....	Yellow.
19....		1-hydroxybenzene-3-carboxylic acid ethyl amide.	Do.

EXAMPLE 12

10 parts of the acid chloride used in Example 4 and sodium-n-butylate, corresponding to 0.5 part of sodium metal, in 50 parts of n-butanol are heated for 5 hours at 70–80°. The reaction mixture is then evaporated to dryness in vacuo and the residue is taken up in a little dimethyl formamide. On pouring this dimethyl formamide solution into 300 parts of cold water, a yellow product is obtained which has the formula:

In the presence of a naphthalene sulphonic acid/formaldehyde condensation product, it dyes polyglycol ter-

55 ephthalate fibres such as Tergal in greenish yellow shades from an aqueous dispersion, sometimes in the presence of a carrier. The dyeings are fast to washing, sublimation and light.

A dyestuff having similar properties is obtained under 60 the same conditions if, instead of the 10 parts of the acid chloride used above, 10 parts of 1-phenyl-3-methyl-4-(2'-chloro - 4"-nitrophenylazo)-pyrazole - 5-one-3'-sulphonic acid chloride are reacted with a solution of 0.5 part of sodium in 50 parts of n-octyl alcohol.

65

EXAMPLE 13

3 parts of the dyestuff obtained according to Example 1 are dispersed in 4000 parts of water. 25 parts of the sodium salt of o-phenylphenol and 25 parts of diammonium phosphate are added to this dispersion and 100 parts of polyglycol terephthalate yarn are dyed for 1½ hours at 95–98°. The dyeing is rinsed and after-treated with sodium hydroxide solution and a fatty alcohol/polyethyl-75 ene oxide condensation product. Under these conditions,

a pure yellow dyeing is obtained which has very good fastness to sublimation and light.

EXAMPLE 14

In a pressure dyeing apparatus, 2 parts of the dyestuff obtained according to Example 2 are finely suspended in 2000 parts of water which contains 4 parts of a formaldehyde/naphthalene sulphonic acid condensation product. The pH value of the dyebath is adjusted to 6-6.5 with 10 acetic acid. 100 parts of polyglycol terephthalate yarn are introduced at 50°, the bath is heated within 30 minutes to 120° and the yarn is dyed for 50 minutes at this temperature. The dyed goods are then rinsed with water, soaped and dried. Under these conditions, a pure yellow dyeing is obtained which is fast to washing, rubbing, light and sublimation.

The dyestuffs described in the other examples produce dyeings of equal quality by this process.

EXAMPLE 15

Polyglycol terephthalate fabric such as Dacron is impregnated in a foulard at 40° with a liquor of the following composition:

20 parts of the dyestuff obtained according to Example 7, finely dispersed in
7.5 parts of sodium alginate,
20 parts of triethanolamine,
20 parts of a fatty alcohol/polyethylene oxide condensation product, and
900 parts of water.

The fabric is squeezed out to a 100% liquor content, dried at 100° and then the dyeing is fixed for 30 seconds at a temperature of 210°. The dyed goods are rinsed with water, soaped and dried. Under these conditions, a yellow dyeing which is fast to washing, rubbing, light and sublimation is obtained.

The dyestuffs described in the other examples produce dyeings of equal quality by this process.

EXAMPLE 16

2.6 parts of the acetone-soluble dyestuff produced according to Example 4 are sprinkled into 1000 parts of a solution of acetyl cellulose in acetone having a solid content of 26%. After adding 20 parts by volume of acetone, the mixture is rolled well in a closed flask until the dyestuff has completely dissolved. The dyed solution is then forced through dies. The fibre so formed is passed through a heated tube and then wound. The vivid yellow coloured fibres have excellent wet and light fastness properties.

EXAMPLE 17

42 parts of the sulfonic acid chloride of the formula

are heated for 6 hours at 70-80° with 18 parts a 3-hydroxypyridine and 18 parts of sodium carbonate in 200 parts of ethyl alcohol and 200 parts of water. The reaction mixture is then cooled and the precipitate formed is filtered off, washed with water and dried under reduced

pressure at 70-80°. The dyestuff so obtained, the composition of which corresponds to the formula

is an orange brown power. After milling with the alkali metal salt of a condensation product of naphthalene sulfonic acids and formaldehyde, the dyestuff described dyes polyethylene glycol terephthalate fibers in pure greenish yellow shades from an aqueous dispersion, sometimes in the presence of a carrier. The dyeings have very good fastness to washing, sublimation and light.

The sulfonic acid chloride used as starting material is obtained by coupling diazotized 1-amino-2-nitrobenzene-4-sulfonic acid with 1-phenyl-3-methyl-5-aminopyrazole and reacting the dyestuff sulfonic acid obtained with phosphorus oxychloride in chlorobenzene.

Dyestuffs having similarly good properties are obtained by reacting the dyestuff sulfonic acid chlorides given in column 2 of the following table under the conditions laid down in the above Example 17 with 3-hydroxypyridine.

TABLE VIII

Ex.	Dyestuff sulfonic acid chloride	Shade of dyestuff on polyester fibers
1.....		Greenish yellow.
2.....		Yellow.
.....		

EXAMPLE 18

7 parts of the azo dyestuff acid chloride, produced by treating the dyestuff obtained on coupling diazotized 1-amino-2-nitro-4-chlorobenzene with 1-(2'-chlorophenyl-5'-sulfonic acid)-3-methyl-5-hydroxypyrazole, with phosphorus oxychloride in tetrachloromethane, are slurried in 150 parts of water and 30 parts of ethanol. After adding 14 parts of sodium carbonate and 6 parts of 3-hydroxypyridine, the reaction mixture is boiled for 18 hours while stirring well. The precipitated dyestuff formed after cooling the reaction mass is washed with a lot of water and dried in vacuo at 60-70°. A preparation produced by milling it with the alkali metal salt of a condensation product of naphthalene sulfonic acids and formaldehyde dyes polyethylene glycol terephthalate fibers such as Terylene or cellulose triacetate fibers in pure greenish yellow shades from an aqueous dispersion, sometimes in the presence of carriers such as o-phenylphenol. The dyeings are fast to washing, sublimation and light.

Similar dyestuffs are obtained under the conditions given in the above example by condensing equivalent amounts of the sulfonic acid chlorides given in column 2

of the following Table IX with corresponding amounts of the hydroxypyridine compounds given in column 3 of the table:

TABLE IX

Example	Dyestuff sulphonic acid chloride	Hydroxypyridine compound	Shade on polyester fibres
1.....		3-hydroxypyridine.....	Greenish yellow.
2.....		do.....	Do.
3.....		do.....	Do.
4.....		do.....	Do.
5.....		2-chloro-3-hydroxypyridine.....	Do.
6.....		3-hydroxypyridine.....	Reddish yellow.

TABLE IX—Continued

Example	Dyestuff sulphonic acid chloride	Hydroxypyridine compound	Shade on polyester fibres
7		2-methyl-3-hydroxypyridine	Reddish yellow.
8		3-hydroxypyridine	Yellow.

We claim:

1. A disperse monoazo dyestuff of the formula

wherein X_1 is a member selected from the group consisting of hydrogen, lower alkyl, lower alkoxy, $-Cl$, $-Br$, $-NO_2$, and $-CN$;

X_2 is a member selected from the group consisting of hydrogen, lower alkyl, lower alkoxy, $-Cl$, $-Br$, $-F$, and $-NO_2$;

X_3 is a member selected from the group consisting of hydrogen, $-Cl$, $-Br$, $-CF_3$, and lower alkoxy-carbonyl,

B_1 is a member selected from the group consisting of phenyl, lower alkyl-phenyl, chloro-phenyl, bromo-phenyl, lower alkoxy-phenyl, lower alkanoylamino-phenyl, naphthyl,

and R is a member selected from the group consisting of primary alkyl with from 4 to 10 carbon atoms, secondary alkyl with from 4 to 10 carbon atoms, phenyl, lower alkyl-phenyl, lower alkoxy-phenyl, chloro-phenyl, bromo-phenyl, lower alkanoylamino-phenyl, hydroxy-lower alkyl-phenyl, carbamyl-phenyl, N-lower alkyl-carbamyl-phenyl, lower alkoxy-carbonyl-phenyl, nitrophenyl, di(lower alkyl)-amino-phenyl, phenoxy-phenyl, pyridyl-(3), chloropyridyl-(3) and methyl-pyridyl-(3);

the radical $-SO_2-OR$ being bonded directly to a carbocyclic aromatic nucleus of B_1 , said monoazo dyestuff being free from water-solubilizing groups which dissociate acid in water.

2. The compound of the formula

3. The compound of the formula

4. The compound of the formula

5. The compound of the formula

6. The compound of the formula

No references cited.
